UNITED STATES PATENT OFFICE.

HIRAM STEVENS MAXIM, OF LONDON, ENGLAND, ASSIGNOR TO THE VICKERS, SONS & MAXIM, LIMITED, OF SAME PLACE.

PROJECTILE FOR ORDNANCE.

SPECIFICATION forming part of Letters Patent No. 662,798, dated November 27, 1900.

Application filed November 6, 1899. Serial No. 735,975. (No model.)

To all whom it may concern:

Be it known that I, HIRAM STEVENS MAXIM, Chevalier of the Legion of Honor, civil and mechanical engineer, a citizen of the United States, residing at 18 Queen's Gate Place, London, England, have invented certain new and useful Improvements in and Relating to Projectiles for Ordnance, of which the following is a specification.

This invention relates to projectiles for ordnance, and has for its object to provide an improved gas-check for preventing or mitigating the erosive action on the bore of the gun, which arises by the incandescent gases of discharge rushing between the projectile and the surface of the gun. In some of the devices patented by myself and others for the purpose of preventing this erosive action semiplastic obturating-rings have been placed on the projectile, these rings being so made that they will expand radially outward against the bore of the gun under the gas-pressure exerted upon a movable or collapsible ring or disk arranged on the base of the projectile with its rim contiguous to the semiplastic ring.

It has been found in practice that it is extremely difficult to make the semiplastic ring of the proper degree of plasticity required—that is to say, if it be too plastic the paraffin wax or tallow with which the ring is provided will on the firing of the gun be suddenly squeezed backward against the pressure of the gases into the space behind the projectile, or if the quantity of the wax or tallow used with the said ring be inadequate the ring becomes compressed into a hard condition and will not with sufficient promptness spread radially outward under the pressure of the gases.

Now according to my present invention and in order to overcome the above-stated objections I so construct and arrange on the base of the projectile, in conjunction with the semiplastic ring, a movable metal ring, disk, or base-piece, which at the instant of firing forces the said plastic ring radially outward against the bore of the gun and then as the projectile moves along the bore acts as a plunger or piston to cause a quantity of wax or tallow or other suitable substance con-

tained in a cavity in the projectile to be continuously forced out radially behind the semiplastic ring (or to the bore of the gun) during the whole or the greater portion of the travel 55 of the projectile along the bore.

In order that my said invention may be clearly understood and readily carried into effect, I will proceed to describe the same more fully with reference to the accompanying drawings, in which—

Figure 1 is a longitudinal section of the rear portion of a projectile provided with my improved gas-check and approximately in the position it occupies within the bore of the 65 gun prior to discharge. Fig. 2 is a similar view, but showing the position of the parts just after the discharge and when the projectile has advanced a short distance along the bore. Fig. 3 is a transverse section taken 70 on the line 11 of Fig. 1. Fig. 4 represents sectional views of the various parts of gas-check and the rear part of the projectile separated from each other, so as to more clearly illustrate their construction. 75

Referring more particularly to Figs. 1 to 4, A is the gun-barrel; B, the projectile; C, the copper driving-band; D, the semiplastic ring, and E the movable metal base-piece. The base of the projectile is reduced to form a circumferential cavity or recess b, Fig. 4, and the said base has also formed therein an annular groove or pocket b', concentric with the aforesaid circumferential cavity. This annular groove communicates with the circumferential cavity by a series of transverse holes or passages b², Fig. 3, which extend through the outer wall b³ of the annular groove. The movable metal ring or base-piece E is constructed with two concentric circular flanges 90 e' e², separated by an annular groove or space e, the flange e' being preferably of greater width than the flange e². The flange e' is adapted to enter the cavity b, while the flange e² is adapted to enter the annular groove b'. 95 This ring E is held in place on the base of the projectile by any suitable means, which will permit of its forward movement when subjected to the pressure of the gases in the gun, but which will not permit of its unintentional detachment from the projectile. In the drawings I have shown for this purpose a flanged

or dished ring F, composed of copper or other suitable metal, which is connected to the base of the projectile by means of screws f¹. Between the said flanged or dished ring and the 5 inner circumference of the movable ring E, I prefer to place a quantity of wax or tallow or other suitable substance f¹, that will act as a gas-check at this point and so prevent the gases of discharge from reaching the annular groove b'. The outer edge or periphery of the said ring F is formed with a lip f², which engages with a shoulder e³, formed in the said ring E. Within the annular groove b' I place the wax, tallow, or other suitable 15 substance to be forced out behind the semi-plastic ring D during the passage of the projectile along the bore.

It will be found advantageous to make the flanges e' e² of the movable ring E loosely 20 fit the recess b and the annular groove b', so that said ring will freely move forward when subjected to the gas-pressure and to provide the said circular recess and annular groove, respectively, with tightly-fitting metal packing-pieces G H, so as to prevent the entrance 25 of the gases of discharge into the said circular recess and annular groove.

I is a band of hemp or other appropriate 30 fibrous material which is interposed between the semiplastic ring D and the driving-band C and which may be treated with paraffin-wax or other substance of a similar nature to render said ring semiplastic. This band may be composed of several rings arranged edge 35 to edge, as shown in Fig. 4.

The movable ring E may be provided at its periphery with a copper band, which when 40 said movable ring shifts under the pressure of the gases will act upon and compress the portion of the semiplastic ring which lies outside the circumference of the movable ring. In most cases, however, I prefer to construct the aforesaid packing-piece G of such a width 45 that it will project at its outer circumference beyond the periphery of the said ring E, as represented in the drawings. It will be found 50 advantageous to form the outer circumference of said packing-piece G, beveled, as shown, so that its strength will be reduced at such part to permit of said circumferential 55 portion to bend rearwardly under the pressure of the semiplastic ring during the passage of the projectile along the barrel.

The annular groove containing the wax or 60 tallow or other substance is preferably only partially filled therewith, so that the flange e² of the movable ring E will not act to compress said substance and force it through the radial passages b² until after the projectile has moved some distance along the bore.

When the gun is fired, the pressure of the powder-gases acting on the aforesaid movable ring E causes the latter to advance toward the base of the projectile and its flange e' to 65 compress the semiplastic ring D, whereby the latter is forced radially outward against the surface of the bore of the gun as the pro-

jectile travels along. The continued advance of the movable ring E as the semiplastic ring is squeezed out permits the flange e² 70 to act upon the material within the annular cavity b', whereby said material is caused to be compressed and driven through the radial passages b² into contact with the said semi-plastic ring D, as shown in Fig. 2, thus assisting in forcing the said ring radially outward against the bore of the gun as the projectile travels along said bore.

I have described the annular groove or pocket b' as containing wax, tallow, or other 80 suitable substance. By "other suitable substance" is of course intended such substance as may be pressed out of the pocket or groove b' through the passage b² into the cavity b behind the semiplastic ring D therein. This 85 may be a substance such as wax or tallow, specifically mentioned, or it may be a substance which is harder or softer than the two substances named. In order, therefore, that a comprehensive term may be employed for 90 the material contained in the pocket or groove b', I call such material "expressible."

What I claim is—

1. The combination with a projectile having a pocket therein containing an expressible substance, of a semiplastic ring and means actuated by the pressure of the explosive charge of the gun applied behind said projectile and independent of other explosive means for forcing said expressible substance 95 into engagement with said ring for expanding the latter, as and for the purpose set forth.

2. The combination with a projectile having a pocket therein containing an expressible substance, of a semiplastic ring at one 105 end of said projectile, and a movable base-piece for forcing said expressible substance into engagement with said ring, and expanding the latter, the said base-piece being actuated directly by the explosion of the propelling charge in the gun behind the projectile 110 and independent of other explosive means, as and for the purpose set forth.

3. The combination with a projectile having a pocket therein containing an expressible substance, of a semiplastic ring at the 115 end of said projectile, and a movable base-piece, one part of which engages said ring, and another part of which fits within said pocket, whereby upon the application of pressure upon the rear side of said base-piece, said ring is spread by said base-piece and said expressible substance is forced in engagement therewith to further expand said ring, as and for the purpose set forth. 120

4. The combination with a projectile having a recess therein, of a semiplastic ring in said recess, and a movable base-piece for forcing an expressible substance into said recess during the passage of the projectile along 130 the bore of the gun, the said base-piece being actuated directly by the explosion of the propelling charge in the gun behind the projectile and independent of other explosive means.

5. The combination with a projectile having a recess therein containing a semiplastic ring, a groove containing an expressible substance and passages between said groove and recess, of a movable base-piece having annular flanges thereon, one of which is adapted to enter said recess and the other of which is adapted to enter said annular groove, as and for the purpose set forth. 45
- 10 6. The combination with a projectile having a recess therein, containing a semiplastic ring, a groove containing an expressible substance and passages between said groove and recess, of a movable base-piece having two concentric flanges thereon, the outer one adapted to enter the recess containing the semiplastic ring and the inner one to enter the groove containing the substance to be forced into said recess through said passages, the quantity of the expressible substance in said groove being such that it only partially fills the same, so as to permit the said movable base-piece to advance a short distance before acting upon and forcing the substance from said groove, 55 as and for the purpose set forth. 60
- 15 7. The combination with a projectile having a recess therein containing a semiplastic ring, a groove containing an expressible substance and passages between said groove and recess, of a movable base-piece in the form of a ring, having two circular flanges thereon which flanges are adapted to enter, respectively, the recess containing the plastic ring and the groove containing the substance to 65 be forced into said recess through said passages, the flange that enters the recess containing the semiplastic ring being of greater width than the other flange, as and for the purpose set forth. 70
- 20 8. The combination with a projectile having a recess therein, containing a semiplastic ring, a groove containing an expressible substance and passages between said groove and 75
- 25
- 30
- 35
- 40

recess, of a movable base-piece having two concentric flanges adapted to lie within said recess and groove and packing-pieces adapted to tightly fit said recesses and groove, as and for the purpose set forth.

9. In a projectile for ordnance, the combination with a semiplastic ring, a movable base-piece having two concentric flanges, and a recess and a groove in the projectile for receiving said flanges, the said groove containing an expressible substance and communicating with said recess of packing-pieces adapted to tightly fit the recess and the groove, the said packing-piece for the recess being of greater width than the flange of the base-ring entering said recess and weakened at its outer periphery substantially as described. 60

10. In a projectile for ordnance, the combination with a semiplastic ring and a movable metallic base-ring, having two circular flanges thereon adapted to respectively engage with a recess and an annular groove in the projectile, of a dished ring for securing the said base-ring to the projectile and of a gas-check interposed between said dished ring and the base-ring substantially as and for the purpose specified. 65

11. In a projectile for ordnance, the combination of a semiplastic ring, of a movable base-piece having two circular flanges thereon for engaging respectively with an annular recess and an annular groove in the projectile, of a metal driving-band and of a fibrous band interposed between said semiplastic ring and the driving-band substantially as and for the purpose specified. 75

In testimony whereof I have hereunto set my hand, in presence of two subscribing witnesses, this 24th day of October, 1899.

HIRAM STEVENS MAXIM.
